His Attorney

UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

WIRELESS-TELEPHONE SYSTEM.

1,313,041.

Specification of Letters Patent.

Patented Aug. 12, 1919.

Application filed August 24, 1916. Serial No. 116,634.

To all whom it may concern:

Be it known that I, ERNST F. W. ALEXANDERSON, a citizen of the United States, residing at Schenectady, in the county of 5 Schenectady, State of New York, have invented certain new and useful Improvements in Wireless-Telephone Systems, of which the following is the specification.

My present invention relates to wireless 10 telephone systems, and more particularly to systems in which a two way conversation may be maintained by wireless means between two widely separated points. In carrying on a telephone communication by 15 wireless various means have been previously employed to allow the carrying on of conversation in two directions. In some cases a throw-over switch has been employed for disconnecting the transmitting apparatus 20 from the antenna and for connecting the receiving apparatus thereto, and after the speaker at one station has talked for a time the switches at the two stations are thrown over to permit transmission of 25 speech from the other station. The operation of these switches has also been rendered automatic by suitable relays which throw the switch over from receiving to transmitting position as soon as the speaker 30 starts to talk into the telephone transmitter. The great disadvantage of such systems, however, has been that the one listening is unable to interrupt the one talking. It has also been proposed to connect both 35 the receiving and transmitting apparatus permanently to the antenna and by means of balanced circuits eliminate the effect of the transmitting apparatus upon the receiving apparatus. Practical difficulties 40 however, have arisen in the operation of such a system and as far as the present applicant is aware no success has ever been obtained with this arrangement.

The object of the present invention is to 45 overcome the disadvantages present with systems of the types referred to and to provide a system in which a continuous two-way conversation may be carried on as readily as in the case of an ordinary wire 50 connection. A further object of the invention is to provide a system whereby any subscriber connected with a central telephone exchange may be put into communication by wireless with any subscriber connected 55 to a telephone exchange at a distant point.

In carrying my invention into effect I provide at each end of the transmission system two antennæ, one for transmitting signals and the other for receiving, the two antennæ being located at a great enough 60 distance from each other so that the effect of the transmitted signals may be eliminated in the receiving apparatus. In addition I provide connections whereby a telephone subscriber connected to a central exchange 65 may be connected simultaneously with both the receiving and transmitting antennæ.

My invention will best be understood by reference to the following description taken 70 in connection with the accompanying drawing in which I have illustrated diagrammatically one way in which my invention may be carried into effect. I have indicated in the drawing connections for two complete 75 stations 1 and 2, which may be located at any distance from each other desired. At station 1 there is a transmitting antenna 3 and receiving antenna 4, and at station 2 a transmitting antenna 5 and a 80 receiving antenna 6. These antennæ are all provided with the usual tuning inductances 7. At station 1 I have indicated a subscriber's circuit 8 connected to a central exchange 9 and connections may be made 85 through this central exchange by means of line 10 to the transmitting antenna and through line 11 to the receiving antenna. The transmitting antenna has connected thereto a source 12 of high frequency alternating current and the telephone currents passing over line 10 may be utilized to control the output of the source of high frequency current by means of a magnetic device 13 which may be of the type described 90 in my U. S. Patent No. 1,206,643. At the receiving antenna 4 there may be connected any desired form of detector and I have indicated diagrammatically a crystal detector 14. The signals which are received 100 may be transmitted from the detecting apparatus through the transformer 15, over the line 11 and through the central exchange to the subscriber's instrument 16, or they may be amplified in any convenient way 105 before they are transferred to line 11, as for example, by means of a relay such as that described in Patent No. 1,038,910 to Von Lieben & Reiz. The arrangement used at station 2 may be an exact duplicate of 110

the one illustrated at station 1 although in the present case I have indicated a line 17 connecting the antennæ 5 and 6 and a branch line 18 extending from this line to the central exchange.

In the operation of this system it will be found desirable to employ different frequencies for the high frequency sources at the two stations and antenna 6 will be tuned 10 for the frequency of source 12 at station 1 and antenna 4 will be tuned for the frequency of the source 12 at station 2. By using two frequencies which are far enough apart the effect of the transmitted signals 15 upon the receiving apparatus at the same station may be eliminated to such an extent as not to interfere with conversation. The distance by which the two antennæ of the station must be separated will of course 20 depend upon the strength of the signals transmitted and the difference in the two frequencies which may be employed.

While I have indicated diagrammatically a certain form of receiving and transmitting apparatus, as well as certain specific 25 connections whereby the subscriber may be connected to the wireless system; it will be apparent that many modifications in the particular form of apparatus used and in 30 the specific manner in which the connections are carried out may be made without departing from the scope of my invention as set forth in the appended claims.

What I claim as new and desire to secure 35 by Letters Patent of the United States, is:—

1. The combination in a wireless signaling system of an antenna for transmitting signals, a source of high frequency energy and apparatus for controlling the same connected to said antenna, a receiving antenna 40 having suitable receiving apparatus operatively connected thereto at all times and located at such a distance from the transmitting antenna that the effect of the transmitted signals may be eliminated in the receiving apparatus, a telephone line, and means for connecting the telephone line simultaneously to both the transmitting and receiving apparatus.

2. Means for carrying on a two-way telephonic conversation between two widely separated points comprising an antenna for transmitting signals, a source of high frequency energy and apparatus for controlling the same connected to said antenna, a receiving antenna having suitable receiving apparatus operatively connected thereto at all times and located at such a distance from the transmitting antenna that the effect of the transmitted signals may be eliminated in the receiving apparatus, a telephone line, means for connecting the telephone line simultaneously to both the transmitting and receiving apparatus, a second telephone line, 55 and means for connecting the second tele-

phone line to two separate antennæ arranged in a manner similar to the first mentioned antenna.

3. In a wireless telephone system, a subscriber's circuit, a central exchange, a transmitting antenna, a receiving antenna located at such a distance from the transmitting antenna that the effect of transmitted signals may be eliminated in receiving apparatus operatively connected thereto at all 75 times and means for connecting the subscriber's circuit through the central exchange simultaneously with both the transmitting and receiving antennæ.

4. In a wireless telephone system, a subscriber's circuit, a central exchange, a transmitting antenna, a receiving antenna located at such a distance from the transmitting antenna that the effect of transmitted signals may be eliminated from the receiving 85 apparatus operatively connected thereto, means for connecting the subscriber's circuit through the central exchange simultaneously with the transmitting and receiving antennæ, a second subscriber's circuit located at a distance from the first subscriber's circuit, a second central exchange to which the second subscriber's circuit is connected, transmitting and receiving antennæ arranged in a manner similar to the first mentioned antennæ, and means for operatively connecting the second subscriber's circuit simultaneously with the second mentioned transmitting and receiving antennæ.

5. Means for carrying on a two-way wireless telephonic conversation between two widely separated stations comprising an antenna at the first station for transmitting signals, a source of high frequency energy of definite frequency and apparatus for controlling the same connected to said antenna, a receiving antenna having suitable receiving apparatus operatively connected thereto at all times, located at such a distance from the transmitting antenna and so arranged 100 that the receiving apparatus will be unaffected by the signals transmitted, a telephone circuit, means for connecting the telephone circuit to both the transmitting and receiving apparatus, a second telephone line, 105 separate transmitting and receiving antennæ at the second station, means for connecting the second telephone line to said antennæ at the second station, the receiving antenna being tuned to the frequency of the high frequency source at the first station and a second source of high frequency energy of a different frequency from the first source connected to the second mentioned transmitting antenna, the receiving antenna at the first station 110 being tuned to the frequency of the second mentioned source of high frequency energy.

6. The combination in a wireless signaling system of an antenna for transmitting signals, a source of high frequency energy 115

of a definite frequency and an apparatus
for controlling the same connected to said
antenna, a receiving antenna tuned to a fre-
quency different from that of said source
5 having suitable receiving apparatus opera-
tively connected thereto at all times and lo-
cated at such a distance from the transmit-
ting antenna that the receiving apparatus

will be unaffected by the signals transmitted,
a telephone line and means for connecting 10
the telephone line simultaneously to both the
transmitting and receiving apparatus.

In witness whereof, I have hereunto set
my hand this 23rd day of August, 1916.

ERNST F. W. ALEXANDERSON.
